[57] CLAIM

The ornamental design for a stool or similar article, as shown and described.

DESCRIPTION

FIG. 1 is a front perspective view showing my new design for a stool or similar article, the corresponding rear view being a mirror image thereof.

FIG. 2 is a top plan view thereof.

FIG. 3 is a side elevational view thereof, the opposite side elevational view being a mirror image thereof.

FIG. 4 is a rear elevational view thereof.

FIG. 5 is a front elevational view thereof.

FIG. 6 is a bottom view thereof.

FIG. 7 is a cross-sectional view taken on line 7—7 of FIG. 2.
